UNITED STATES PATENT OFFICE.

WILLIAM F. DIESEL, OF ROCHESTER, AND WILLIAM R. PRICE, OF NEW YORK, N. Y.,
ASSIGNORS TO SARGENT AND GREENLEAF, INC., OF ROCHESTER, NEW YORK, A
CORPORATION OF NEW YORK.

LOCK.

1,417,148.

Specification of Letters Patent. Patented May 23, 1922.

Application filed April 13, 1921. Serial No. 461,137.

To all whom it may concern:

Be it known that we, WILLIAM F. DIESEL, of Rochester, in the county of Monroe and State of New York, and WILLIAM R. PRICE, of New York, in the county and State of New York, have invented certain new and useful Improvements in Locks; and we do hereby declare the following to be a full, clear, and exact description of the same, reference being had to the accompanying drawings, forming a part of this specification, and to the reference numerals marked thereon.

This invention has to do with locks and relates more particularly to the variety employing key operated tumblers controlling the bolt, such as are commonly employed on doors and other closures, the chief object of the invention being to provide a simple and economical lock of the above character having convenient tumbler adjusting means for selectively adapting a given lock for operation by any one, exclusively, of a plurality of keys, so that the key to which the lock responds may be readily changed from time to time to render previous keys inoperative, and duplicate locks may be easily rendered responsive to different keys. To these and other ends the invention consists in certain improvements and combinations of parts, all as will be hereinafter more fully described, the novel features being pointed out in the claims at the end of the specification.

35 In the drawings:

Figure 1 is an external view of one side of a lock embodying the present invention.

Figure 2 is a similar view of the other or rear side thereof.

40 Figures 3 and 4 are views similar to Figure 1 with the forward side of the casing removed and showing the operating parts in different positions.

Figure 5 is a sectional view substantially 45 on the line 5^a—5^a of Figure 4.

Figure 6 is a view of the barrel of the lock as seen from its rear end.

Figures 7 and 8 are views of a complementary key bit and portable key used with 50 the lock.

Similar reference characters throughout the several views indicate the same parts.

This invention provides a lock of the key operated type generally applicable to doors 55 and other closures and having means for

changing the key to which the lock responds, comprising preferably a casing 10 having a rear side wall 11 and a removable front wall 12. The present embodiment of the invention is suitable for attachment to the inner 60 side of a closure such as a door and is formed at the corners of the casing with openings 13 to receive screws or other means securing the lock to the closure. The removable front wall 12 which is thus placed 65 against the closure in use is held on the casing as by means of screws 14 entering threaded openings in lugs 15 carried interiorly by the casing. One end wall of the latter is provided with an opening in which 70 slides a bolt 16, Figures 3 and 4, which is guided by the sides of the said opening and is bifurcated at its other end within the casing as at 17 to slidably engage a post 18 on the casing. The bolt is thus supported 75 and guided at both ends and also carries a lug 19 for engagement with a stop 20 on the casing to limit the outward movement of the bolt, the inner movement of the same being limited by the engagement of its end 80 with the casing.

The means for sliding the bolt comprises 85 preferably a notch or recess 21 in its lower side with which engages an arm 22 on a rotatable element or barrel 23 extending transversely through the casing and supported by its front and rear walls. The forward side of the lock, which, as stated, is adapted to be placed against the inner side of a closure, is formed with a forwardly extending 90 circular wall or boss 24 adapted to extend through a corresponding opening in the closure to the forward side of the latter. The barrel 23 extends through boss 24 which has an open end provided with a bearing 25 95 rotatably supporting a flange 26 on the end of the barrel. The latter thus extends to the outer surface of the closure to expose an opening or keyhole with which it is provided, as described hereafter. The rear wall of the casing is provided with an opening aligned with boss 24 and formed with a bearing 100 surface 27 rotatably supporting a flange 28 on the corresponding end of the barrel so that the latter is adapted to rotate in the 105 casing and, by means of its arm 22, to slide the bolt from the position shown in Figure 4 to that shown in Figure 5 and vice versa.

The means for turning the barrel comprises an opening or keyhole 29 extending 110

inwardly from its forward end and adapted to receive a key 30. The movement of the barrel and of the bolt is controlled, as usual in this type of lock, by a fence 31, in the 5 present instance carried by the bolt, and co-operating with a set of tumblers 32, each pivotally supported at one end on post 18 and formed at its opposite end with a slot 33 to receive the fence. The slots 33 of the different tumblers, of which, in the present instance, there are six, are located at different distances from the lower sides of the respective tumblers, according to the particular system of the lock, and as well understood in the art, the tumblers must be so adjusted as to bring the slots 33 of all of them into registry with fence 31 before the bolt can be retracted. The tumblers are adjusted in this manner by key means inserted 10 in the barrel and are normally urged toward the latter for cooperation with such key means by a leaf spring 34 carried by each tumbler and bearing at its opposite end against a lug on the casing.

25 The key means for adjusting the tumblers comprises the key 30 referred to above as adapted for insertion in the opening or key-hole 29 in the forward end of the barrel, and also a hole 35 extending inwardly of the barrel from its rear end and receiving a part or key bit 36 adapted to be inserted at the rear side of the lock. The keyholes 29 and 35 are so arranged relative to each other as to bring the key 30 and key bit 36 when 30 inserted in the lock side by side with their tumbler actuating portions under the set of tumblers. Key bit 36 as shown in Figure 5 has a blank portion 37 arranged to engage a flange 38 on the barrel to limit its movement inwardly of the lock so that while readily inserted in and removed from the lock at the rear side of the latter with the bolt extended, the key bit cannot be removed or gotten at from the forward or front side 35 of the lock.

40 The key bit 36 and the bit of key 30 have their tumbler actuating parts constructed in a complementary manner, the one adapted to actuate one or more, but not all of the tumblers, and the other to actuate those tumblers not actuated by the first. In the 45 particular instance shown, key 30 is adapted to actuate the first, third, fourth and sixth tumblers in order from the rear side of the lock, while the bit 36 is adapted to actuate the second and fifth tumblers. Thus neither the key 30 nor bit 36 can be used separately to operate the lock, but when used together they are adapted to raise all of the tumblers 50 so as to bring their slots 33 in registry with the fence and permit the bolt to be withdrawn.

55 Key 30, as shown in Figure 8, is of the common portable variety adapted to be inserted in the lock to operate the latter and

removed after such use. The key bit 36 on the other hand is adapted to be inserted in the lock at its rear side when the closure is open and to be left in the lock to maintain the latter responsive at all times to the 70 complementary key 30 which may then be inserted, operated and withdrawn without manipulation of bit 36. The rear side of the lock is preferably provided with a cover plate 39 for the keyhole 35, pivotally 75 supported at 40 and adapted after the key bit has been inserted in the barrel to be snapped back to the position shown in Figure 2 to hold the key bit in place. Also, a small opening 41 is preferably formed in the end 80 of the key bit adjacent the rear end of the barrel so that any small hooked implement may be inserted through the space provided by the adjacent keyhole 29 and into opening 41 for withdrawing the key bit from the 85 barrel after the keeper plate 39 has been moved to one side.

90 It is apparent that a large number of complementary pairs of portable keys and key bits similar to the pair described above may be constructed and each pair employed in the complementary manner described for operating the lock but the lock is responsive, of course, only to a portable key complementary to the particular key bit inserted in 95 the lock so that the key bit employed at any time may be removed and replaced by a different one, thus rendering the portable key previously used with the lock inoperative. This substitution of one key bit for 100 another, moreover, is readily affected by anyone without removing the lock, requiring no special knowledge or skill.

105 As apparent from the description and drawing the construction is exceedingly simple, reliable and inexpensive to manufacture, and provides a lock having a wide range of utility. Thus a series of duplicate locks may be used each having the same key bit 36 inserted therein and operated by 110 duplicate keys, and periodically or whenever desired a new key bit may be easily substituted in each lock thus rendering the portable key previously used useless and requiring a new portable key complementary 115 to the new key bit for actuation of the lock. Or, a series of locks may be employed, as for instance in a security vault, each having a different key bit inserted therein and operable by a different portable key. By varying the tumbler construction, of course, the same key bit may be employed for use with a number of different portable keys. Should the key of a given lock become lost, a new key bit may be obtained and readily substituted in the lock for the old one, thus rendering the lock inoperative by the previous key and responsive only to a new portable key corresponding to the new key bit in the lock. 125 Various modifications of the construction 130

and uses described may, of course, be made, the present embodiment being intended merely by way of illustration of the principles involved and a preferred practical application thereof.

5 We claim as our invention:

1. A lock comprising a bolt, a plurality of tumblers, an element for moving the bolt under control of the tumblers, a part applicable to one side of the lock for adjusting certain of said tumblers, and a key applicable to another side of the lock for adjusting others of said tumblers and releasing said bolt.
- 10 2. A lock comprising a bolt, a plurality of tumblers, an element for moving the bolt under control of the tumblers, a part corresponding to certain of the tumblers applicable to said element on one side of the lock, and a complementary key corresponding to the remainder of the tumblers applicable to said element on the other side of the lock for moving the same, adjusting said tumblers and moving the bolt.
- 15 3. A lock comprising a bolt, a plurality of tumblers, an element for moving the bolt under control of the tumblers having openings therein communicating with opposite sides of the lock, a part corresponding to certain of the tumblers adapted for insertion in an opening of said element on one side of the lock, and a key corresponding to others of the tumblers adapted for insertion in the opening of said element on the other side of the lock for moving said element and part, adjusting all of said tumblers and moving the bolt.
- 20 4. A lock comprising a bolt, a plurality of tumblers, an element for moving the bolt under control of the tumblers, a key for adjusting certain of said tumblers adapted to be inserted in an opening in one side of the lock for operating the latter and to be removed after such operation, and a part for adjusting the others of said tumblers adapted to be removably inserted in an opening in the other side of said lock and to remain therein to maintain the lock responsive to said key.
- 25 5. A lock comprising a bolt, a set of

tumblers, a barrel for moving the bolt under control of said tumblers, said barrel having openings in its ends communicating with opposite sides of the lock, a key for detachable insertion in one of said barrel openings to adjust certain of said tumblers, and a removable part adapted to be inserted in the other of said barrel openings and to remain therein to adjust the others of said tumblers and permit said key to turn said barrel and move the bolt.

55 6. A lock comprising a casing, a bolt therein having a fence, a single set of tumblers cooperating with said fence, a barrel for moving the bolt extending at its ends through opposite sides of said casing and provided with an opening at each end, a portable key adapted to be removably inserted in one of said barrel openings to adjust certain of said tumblers, and a removable key bit for adjusting the others of said tumblers inserted in the barrel opening on the opposite side of the lock from said key and adapted to remain in the lock to complement said portable key and permit the latter to turn the barrel and move the bolt.

7. A lock comprising a bolt, an element for moving the bolt, a plurality of tumblers controlling movement of the bolt, and a pair of removable complementary key bits adapted to be inserted from opposite sides of the lock for cooperating with each other to adjust said tumblers and permit movement of the bolt, one of said key bits being portable and the other adapted to remain in the lock for cooperation with said portable bit.

8. A lock comprising a bolt, an element for moving the bolt, a plurality of tumblers controlling movement of the bolt, a portable key adapted to be inserted and removed at one side of the lock and to adjust certain of said tumblers, a key bit for adjusting the others of said tumblers adapted to be inserted and removed at the opposite side of said lock and to remain therein for cooperation with said portable key, and means for removably holding said key bit in the lock.
